UNITED STATES PATENT OFFICE.

HAROLD T. MAITLAND, OF SHARON HILL, PENNSYLVANIA, ASSIGNOR TO SUN OIL COMPANY, OF PHILADELPHIA, PENNSYLVANIA, A CORPORATION OF NEW JERSEY.

APPARATUS FOR TREATING OILS.

Application filed April 19, 1921. Serial No. 462,650.

To all whom it may concern:

Be it known that I, HAROLD T. MAITLAND, a citizen of the United States, residing at Sharon Hill, county of Delaware, and State of Pennsylvania, have invented a new and useful Improvement in Apparatus for Treating Oils, of which the following is a full, clear, and exact description, reference being had to the accompanying drawings, which form a part of this specification.

The object of my invention is to provide an apparatus for digesting and mechanically masticating mineral oils. I have found it especially serviceable in the treatment of the "sludge" formed as a precipitate in the usual acid treatment of lubricating oil stock, whereby the excess mineral acid is removed from the sludge, thereby producing a saponifiable oil in accordance with the description contained in applications filed by me, namely, Serial No. 290,228, filed April 15, 1919, and Serial No. 439,948, filed January 26, 1921. The apparatus, however, is not limited to this particular use and may be found available for use in other processes. In the description of the operation, however, I shall set forth the manner in which it is operated in treating the sludge above named.

A preferred embodiment of the invention is shown in the accompanying drawings, in which—

Fig. 1 is a vertical sectional view of the digester.

Figs. 2 and 3 are enlarged cross-sections at 2 and 3 Figure 1.

The digester comprises a stationary upright cylindrical vessel preferably made in three sections, *a*, *b* and *c*, the two lower sections *a* and *b* being steam-jacketed along their upright walls and the lowermost section being steam-jacketed in its bottom. These steam jackets *d* are adapted to withstand a pressure of one hundred pounds to the square inch. The inner wall of the digester should be covered with some acid-resisting metal or composition if it is to be used for the purpose hereinbefore specified.

The upper section *c* is provided with a discharge nozzle *e* which, in the normal operation of the apparatus, is constantly open, as hereinafter described.

Extending axially of the vessel is a rotatable hollow shaft *f* turning in a bearing *g* in the bottom of the digester, in an intermediate bearing *j* hereinafter described and

in a bearing *h* on a frame *i* mounted on the top of the digester. The hollow shaft *f* communicates at its upper end with a pipe *k* for admission of a fluid—preferably steam when the apparatus is used for the purpose hereinbefore specified.

The hollow shaft *f* has secured to it a bevel gear *m*, which is driven by a bevel gear *n* on a driving shaft *o*, which turns in bearings on the top of the digester.

Across the digester extend two interfering bars *r* and *s*. The lower bar *r* is preferably carried by the lower section *a* and the upper bar is preferably carried by the middle section *b*. These bars are preferably arranged at right angles to each other. They may be shaped as desired. They are preferably of cylindrical shape. The lower bar *r* carries one of the bearings (*j*, hereinbefore mentioned) for the upright hollow shaft.

Secured to the hollow shaft *f* are paddles or stirrers *p*, which, besides performing the function of stirring and agitating the material undergoing digestion, cooperate with the fixed bars *r* and *s* to "masticate" the material, as hereinafter described. These paddles are hollow and communicate with the interior of the shaft *f*, and hence receive steam and are thus maintained highly heated. They are of oblong or oval shape with their longer cross dimensions extending obliquely but at a more acute angle to the horizontal than to the vertical. They are thus provided with a sweep or pitch adapted to produce a lifting effect upon the material undergoing treatment. The more nearly adjacent paddles are preferably arranged angularly to each other. Each paddle should be provided with a small orifice *q* located preferably in its outer end, to allow the escape of steam or water of condensation.

Another pair of paddles or stirrers *t*, secured to the lower end of the shaft, perform functions similar to those performed by the paddles *p*. This stirrer is of arcuate shape in its lengthwise extension, conforming in this respect to the spherical-like shape of the bottom of the digester. It is arranged quite close to such bottom and, like the other paddles, is hollow. It is of oval shape in cross-section and is so positioned that its longest cross-dimension extends obliquely. This stirrer also performs the function of admitting into the lower part of the digester steam (or other fluid), which descends

through the hollow shaft *f*; the stirrer being provided, for this purpose, with a number of perforations *u* arranged along that edge thereof which, in rotation, is the rear edge. The escape of steam through these orifices also assists in further raising the material raised by the stirrer.

Normally the main treating fluid admitted into the digester is hot water. For this purpose a hollow casting *v* is secured to the bottom of the digester, and is adapted for connection with an inlet pipe. Openings *w* in the lower shaft-bearing *g* afford communication between the casting *v* and the interior of the digester.

In the treatment of sludge, the digester is filled with water up to or somewhat below the outlet *e*, the water having a temperature of about 150-200 degrees F. After the introduction of the sludge, the same is thoroughly mixed with the water and mechanically masticated. The admission of water is ordinarily continuous, although for certain purposes its introduction may be intermittent. The desired temperature is maintained throughout the operation by means, first, of the constant access of fresh hot water; second, the steam jackets; and third, such live steam as is blown in through the orificed paddles *t*. The surplus liquid, which comprises the lighter constituents of the mixture, overflows at the outlet *e*. These lighter constituents consist of mineral acid and certain other compounds.

The driving mechanism should be so governed as to permit of varying the speed of rotation of the shaft *f* and the paddles carried thereby in accordance with the condition, at any given time, of the material being treated. So, also, the temperature of the contents may be varied to suit conditions. The sludge is tested for acidity at intervals. When the content of mineral acid has been reduced to the extent desired, the admission of water and steam is cut off, the rotation of the shafts and stirrers stopped, and the excess washing liquid is siphoned or drawn off.

It is of importance, at least in the foregoing treatment of sludge, that no air be permitted to mix with the sludge before the sulfur dioxide has been practically eliminated, as the buoyancy of the air causes the small particles of sludge to rise to the surface and to be carried away with the washing liquid. The residual compounds settling to the bottom of the digester are saponifiable oils containing some dissolved or suspended mineral oils.

The apparatus herein described contains inventive features in common with the specifically different apparatus set forth in an application filed by me June 21, 1918, Serial No. 241,210, and may be said to be a simplified improvement on said earlier apparatus.

Having now fully described my invention, what I claim and desire to protect by Letters Patent is:

1. A digester and mechanical masticator particularly adapted for the treatment of sludge formed as a precipitate in the usual acid treatment of mineral oil lubricating stock, comprising a steam-jacketed upright vessel, an upright shaft extending axially through the vessel, stirrers secured to and extending laterally of the shaft at different levels, fixed cross-bars extending across the interior of the vessel at different levels, the stirrers acting to mix and agitate the contents of the vessel and the cross-bars cooperating with the stirrers to masticate the contents, there being an open space in the vessel above the stirrers and cross bars, an opening in the lower part of the vessel for the inflow of the treating fluid and an overflow outlet in the upper part of the vessel opening into said open space for carrying off the lighter constituents of the mixture, said constituents being otherwise confined from escape from the lower part of the vessel.

2. A digester and mechanical masticator comprising an upright vessel, a vertical hollow shaft extending axially therethrough and adapted to receive a heating medium, laterally extending hollow stirrers secured to the shaft at different levels and communicating with the interior of the shaft and thereby maintained heated, laterally extending fixed elements at different levels within the vessel, the laterally extending stirrers being substantially wider along one axis than along an axis perpendicular thereto, the stirrers being so positioned that the longer axis extends at an acute angle to the horizontal, and means to rotate the shaft in such direction that the upwardly inclined surfaces of the stirrer face in the direction of rotation whereby the stirrers act to mix, agitate and lift the contents and also cooperate with the fixed elements to mechanically masticate the contents.

3. A digester and mechanical masticator comprising an upright vessel, a vertical shaft extending axially therethrough, laterally extending stirrers secured to the shaft at different levels, laterally extending fixed elements within the vessel at different levels, the several stirrers being substantially wider along one axis than along an axis perpendicular thereto, the stirrers being so positioned that the longer axis extends at an acute angle to the horizontal, and means to rotate the shaft in such direction that the upwardly inclined surfaces of the stirrer face in the direction of rotation whereby the stirrers act to mix, agitate and lift the contents and also cooperate with the fixed elements to mechanically masticate the contents; there being an inlet for the treating

liquid in the lower part of the vessel and an overflow outlet for the lighter constituents of the mixture in the upper part of the vessel above the stirrers and fixed elements, said 5 constituents being otherwise confined from escape below the highest level of the mixing, agitating and masticating mechanism.

4. A digester and mechanical masticator comprising a vessel, rotatable hollow stirrers 10 adapted to impart a rotary mixing movement to the contents of the vessel, elements adjacent to said stirrers and cooperating therewith to effect mastication of the contents, and means to introduce heated treating 15 fluid to the vessel through said stirrers and also independently thereof concurrently with the masticating operation, the vessel being provided above the upper level of said mixing and masticating mechanism 20 with an open space and communicating therewith an overflow outlet to carry off the lighter constituents as the digestion and mastication proceeds and otherwise confining said constituents from escape from being 25 low said level.

5. A digester and mechanical masticator

comprising an upright vessel, a vertical hollow shaft for the reception of treating liquid extending axially through the vessel and, a laterally extending hollow stirrer secured 30 to the shaft, there being an opening at the bottom of the vessel for the inflow of treating liquid and an overflow outlet in the upper part of the vessel for carrying off with 35 said fluid the lighter constituents of the mixture treated, said stirrer being substantially wider along one axis than along an axis perpendicular thereto, the stirrer being so positioned that the longer axis extends at an acute angle to the horizontal 40 and being provided with discharge orifices along its upper inner wall about in line with said longer axis, whereby the stirrers act to lift as well as to mix and agitate 45 the contents both mechanically and by ejection of fluid.

In testimony of which invention, I have hereunto set my hand, at Sharon Hill, Delaware County, Penna., on this 14th day of April, 1921.

HAROLD T. MAITLAND.
